No. 784,879.

PATENTED MAR. 14, 1905.

S. W. PHELPS.

SAND BOX FOR STREET RAILWAY CARS.

APPLICATION FILED AUG. 29, 1904.

UNITED STATES PATENT OFFICE.

SIDNEY W. PHELPS, OF GLOBE VILLAGE, MASSACHUSETTS.

SAND-BOX FOR STREET-RAILWAY CARS.

SPECIFICATION forming part of Letters Patent No. 784,879, dated March 14, 1905.

Application filed August 29, 1904. Serial No. 222,488.

To all whom it may concern.

Be it known that I, SIDNEY W. PHELPS, a citizen of the United States, residing at Globe Village, in the county of Worcester and State 5 of Massachusetts, have invented a new and useful Sand-Box for Street-Railway Cars, of which the following is a specification.

This invention relates to a construction for sanding the rails of street-railways.

10 The especial object of this invention is to perfect and improve the sand-box for street-railways which is described and claimed in United States Letters Patent No. 641,887, granted to me January 23, 1900.

15 To these ends this invention consists of the sand-box for street-railways and of the combinations of parts therewith, as hereinafter described, and more particularly pointed out in the claims at the end of this specification.

20 In the accompanying drawings, Figure 1 is a perspective view showing the connections from an operating-handle to two sand-boxes, one sand-box being located at each side of a car. Fig. 2 is a sectional view of one of the

25 sand-boxes and the reservoir connected therewith. Fig. 3 is a perspective view of one of the sand-boxes. Fig. 4 is a sectional plan view of the same. Fig. 5 is a perspective view of the discharge-pipe and of the means for flexibly supporting the same in a car-truck, and

30 Fig. 6 is a transverse sectional view of the adjustable joint for the discharge-pipe yoke.

In my prior patent before referred to I have disclosed and claimed a sand-box construction 35 which is controlled by a lever located on the dashboard of the car in position to be reached by the motorman and which is operated in the same manner as the controlling-lever of the rheostat and of the air-brake. In my previous patent the sand was discharged through a 40 curved pipe carried by the sand-box itself.

One especial object of the present invention is to provide for discharging the sand more accurately upon the rails. I accomplish this 45 result by employing discharge-pipes which are flexibly mounted upon the truck-frames. A special construction is used for mounting the discharge-pipes so that said pipes may be set

to different angles and will be free to swing or turn in any direction. 50

The discharge-pipes are connected with their respective sand-boxes by means of flexible hose-pipes, so that in passing around curves the turning of the truck-frames with respect to the car-body will not disarrange the parts, 55 the mounting of the discharge-nozzles providing an efficient discharge of sand in front of the wheels under all conditions.

Further objects of this invention are to support the sand-boxes from the floor or body 60 portion of the car in such a way that the sand will be protected from the entrance of water and to combine the sand-boxes at opposite sides of a car with a single operating-handle.

Referring to the accompanying drawings 65 and in detail, 10 designates a bracket which may be secured to the car-dasher or other convenient support. Pivots mounted in the bracket 10 and extending down through the floor of the car is a shaft 11, having a controlling-lever 70 12 at its upper end. Pivots connected with a crank-arm extending from the shaft 11 is a link 13. Adjustably fastened to opposite sides of the link 13 by means of clamps 14 are the arms or extensions 15. Each of the arms 15 75 controls the discharge of sand from one of the sand-boxes, and a description of one set of connections from one of the arms 15 will therefore be sufficient. As shown, each of the arms 15 is pivotally connected with a lever 16, the 80 other end of the lever 16 being connected by a link 17 to a cut-off plate or shutter 18. The cut-off plate or shutter 18 controls the discharge of sand from the sand-box.

The sand-box and the manner in which the 85 same is fastened in place in a car are most clearly illustrated in Figs. 2 to 4, inclusive. As shown in these figures, each of the sand-boxes is provided with a flange 19, which extends up through the floor of a car-body B, 90 and also formed with the sand-box is a flange 20, which is bolted to the under side of the floor of the car-body B.

Connected with the sand-box and fitting down inside thereof is a tapering reservoir or 95 hopper 21, the reservoir 21 being preferably

located under a car-seat. By having the lower end of the reservoir or hopper 21 fitted inside of the upper edge of the flange of a sand-box, which flange extends slightly above the floor, 5 I have provided a joint between the hopper and the box itself which will not permit the water to run from the top of the floor down into the sand.

Mounted in the sand-box is a shaft 22, carrying 10 stirring-arms and the cut-off plate or shutter 18. The lower end of the shaft 22 is mounted in a support or bracket 23.

Fitted on the lower part of the sand-box is a funnel 24. Connected with the lower end 15 of the funnel 24 is a flexible hose or pipe 25, which connects to a discharge-pipe.

The discharge-pipe and the method of supporting the same in a truck-frame A are most clearly illustrated in Figs. 5 and 6. As shown 20 in these figures, 26 designates the discharge-pipe, which is connected at its upper end to the flexible hose 25.

In order to provide an adjustable and flexible support for the discharge-pipe, I employ 25 a bearing-plate 27 having a partially-spherical bearing. Mounted in the bearing-plate 27 is a supporting-yoke having a partially-spherical bearing 28 which fits the plate 27, these parts being fastened together by means 30 of a bolt 29. The head of the bolt 29 is rounded, and the bolt-hole through the part 28 is enlarged, so that the yoke can be turned or adjusted to any desired angular position, this universal adjustment of the yoke being especially 35 adapted for the application of sand-boxes to various styles and types of truck-frames. The discharge-pipe 26 is provided near its center with a ring 31, and connecting the ring 31 with the arms of the supporting-yoke are two oppositely-disposed tension-springs 30. By means of this construction 40 the discharge-pipes may be positioned and fitted to different styles of truck-frames, and when fastened in place the discharge-pipes 45 will be mounted so that they will be free to be turned or swung in any direction.

I am aware that changes may be made in the construction of my sand-boxes by those who are skilled in the art without departing 50 from the scope of my invention as expressed in the claims. I do not wish, therefore, to be limited to the form I have herein shown and described; but

What I do claim, and desire to secure by Letters Patent of the United States, is—

1. In a construction of the class described, the combination of a sand-box mounted on the body of a car, a discharge-pipe flexibly mounted on a truck-frame, and a flexible hose 60 connecting the sand-box and discharge-pipe.

2. In a construction of the class described, the combination of a sand-box mounted on the body of a car, a discharge-pipe in the

truck-frame supported near its center so as to be free to be swung or turned in any direction, and a flexible hose connecting the sand-box and discharge-pipe. 65

3. In a construction of the class described, the combination of a sand-box mounted on the body of a car, a discharge-pipe, means 70 for supporting the discharge-pipe in a truck-frame, comprising a yoke with oppositely-arranged tension-springs connecting the arms of the yoke substantially with the center of the discharge-pipe, whereby the discharge-pipe is free to be swung or turned in any direction, and a hose connecting the sand-box and discharge-pipe. 75

4. In a construction of the class described, the combination of a sand-box mounted in a 80 car-body, a discharge-pipe, means for supporting the discharge-pipe in a truck-frame, comprising a yoke having a ball-and-socket joint, and means for clamping the yoke in different adjusted positions, and a hose connecting the discharge-pipe and the sand-box. 85

5. In a construction of the class described, the combination of a sand-box mounted in a car-body, a discharge-pipe, means for mounting the discharge-pipe in a truck-frame, comprising a yoke, a bearing-plate therefor, the yoke having a ball-and-socket connection with the bearing-plate, a bolt fastening the yoke in different adjusted positions, oppositely-arranged tension-springs connecting the arms 90 of the yoke substantially with the center of the discharge-pipe, whereby the discharge-pipe is free to swing or turn in any direction, and a hose connecting the discharge-pipe and the sand-box. 95

6. In a construction of the class described, the combination of a sand-box, means for fastening the sand-box to the under side of a car-floor so that its upper edge will extend up above the surface of the floor, a reservoir 105 or hopper fitted inside of the sand-box, a discharge-pipe flexibly mounted in the truck-frame so as to be free to turn or swing in any direction, and a hose connecting the discharge-pipe and sand-box. 110

7. In a construction of the class described, the combination of a vertical shaft having a controlling-lever at its upper end, means for mounting the shaft in position to be operated by the motorman of an electric car, a link 115 extending from a crank-arm of the vertical shaft, two sets of connections from the link, one set of connections controlling the discharge of sand from a sand-box at one side of the car, and the other set of connections controlling the discharge of sand from a sand-box at the other side of the car, a discharge-pipe for each sand-box, means for supporting each of the discharge-pipes in a truck-frame, comprising a bearing-plate, a yoke having 120 ball-and-socket connection with the bearing- 125

plate, oppositely - arranged tension - springs connecting the arms of the yoke substantially with the center of a discharge-pipe, whereby the discharge-pipe will be free to be swung 5 or turned in any direction, and a hose connecting each discharge-pipe with its sand-box.

In testimony whereof I have hereunto set

my hand in the presence of two subscribing witnesses.

SIDNEY W. PHELPS.
